UNITED STATES PATENT OFFICE.

JOHN GOLDBERG, OF HOPKINS, MINNESOTA.

FURNACE REGULATOR.

Application filed November 22, 1926. Serial No. 149,955.

This invention relates to a regulator for heating furnaces, one of the objects being to provide a novel form of thermostat for actuating the draft controlling devices so 5 that a substantially uniform temperature can be maintained.

Another object is to provide a regulating flue and damper so positioned as to not only control the draft but also to withdraw from 10 the room the cold and impure air adjacent the floor.

With the foregoing and other objects in view which will appear as the description proceeds, the invention resides in the combination and arrangement of parts and in the 15 details of construction hereinafter described and claimed, it being understood that changes in the precise embodiment of the invention herein disclosed may be made 20 within the scope of what is claimed, without departing from the spirit of the invention.

In the accompanying drawings, the preferred form of the invention has been shown.

25 In said drawings,

Figure 1 is a side elevation of a furnace having the present improvements combined therewith.

Figure 2 is a plan view of the thermostat 30 and a portion of the pipe to which it is attached.

Referring to the figures by characters of reference 1 designates a heating furnace which, in the present instance, is designed 35 as a part of a steam heating system, one of the steam pipes leading from the furnace being indicated at 2. The smoke pipe has been shown at 3. Ordinarily the smoke pipe is provided at a point between the furnace and the chimney with a damper located 40 directly thereon. In the present instance, however, a flue 4 opens downwardly into the top portion of the smoke pipe and extends therefrom to a point below the smoke 45 pipe and close to the floor where it is extended substantially horizontally and is provided with an obliquely disposed intake end 5. Hingedly connected to this end is a plate 6 constituting a damper, the plate normally 50 resting by gravity on the end 5 so as to close it.

A lever 7 which can be adjustably connected to a supporting bracket 8, is located at a point above the furnace and has an 55 operating wire 9 or the like extending from one end thereof to the damper 6. The other

end of the lever 7 is connected by a wire 10 or the like to the draft door 11 of the furnace which is held normally closed by gravity, this door being hinged at its upper end 60 as shown at 12. The connecting wire 10 or the like is mounted on guide sheaves 13 and 14 and it is preferred that the flexible connection 10 be provided with a screw threaded stem 15 on which a sleeve 16 is adjustably mounted. This sleeve has terminal collars 17 and 18 and is located close to the pipe 2. The damper 6 and door 11 are substantially balanced so as to remain in any given position during the lost motion of the 70 thermostat.

A thermostat indicated generally at 19 is attached at one end to the pipe 2, preferably by means of U-bolts 20 which straddle the pipe and engage the thermostat, these bolts serving to hold the thermostat pressed close to the pipe. The free end portion of the thermostat has an ear 21 in which the sleeve 16 is loosely mounted. Said thermostat is preferably formed of two layers of 80 metal having different coefficients of expansion. Thus when the thermostat is unheated or only slightly heated the damper 6 will remain closed while the door 11 will be held open as shown in Figure 1. However when 85 the temperature of the fluid in the pipe 2 is raised to a predetermined degree, the thermostat will be caused to bow downwardly with the result that the ear 21 will come against and shift the collar 18. Consequently a pull will be exerted through the connection 10 upon one arm of the lever 7, thereby allowing the door 11 to close while at the same time said lever 7 will pull on the connection 9 so as to open the damper 6. 90 Thus the fire will be checked and as the temperature of the heating fluid falls to a predetermined degree the thermostat will gradually straighten out, thereby allowing the damper 6 and the door 10 to return to their 95 normal positions as shown in Figure 1. By having the ear 21 between spaced collars 17 and 18, a certain movement of the thermostat is permitted without actuation of the damper and door. The sleeve is adjustably 100 mounted so as to advance or retard the actuation of the damper and door and the lever 7 is adjustably mounted so as to regulate the extent of movement of the damper and door when actuated.

105 While the thermostat has been shown attached to a pipe designed primarily for con-

ducting steam, it is to be understood that it can also be attached to a hot water pipe or to a hot air pipe, this depending on the type of furnace used.

5 By arranging the damper 6 close to the floor, the checking of the furnace will result in the withdrawal of the cold impure air close to the floor and thus more helpful conditions will result than where the damper 10 is located as ordinarily.

What is claimed is:

1. The combination with a furnace having a draft door and a damper adapted to be closed by gravity, and a pipe for conducting heated fluid from the furnace, of an adjustably mounted lever, a connection between the lever and the damper, a connection, including a screw threaded portion, between the lever and the door, a thermostat attached 15 to and adapted to be actuated by the heat of the contents of the pipe, and an adjustable lost motion connection between the thermostat and the threaded portion.

2. The combination with a heating furnace including a damper adapted to be closed by gravity and a pipe for conducting heated

fluid from the furnace, of a lever adjustably mounted, a connection between the lever and the damper, a threaded stem connected to the lever, a member adjustably mounted on the stem and having spaced collars, a thermostat secured to the pipe and adapted to be actuated by the heat of the contents of the pipe, and means carried by the thermostat for slidably engaging said member between the collars.

3. The combination with a furnace having a draft door, a damper adapted to be closed by gravity, and a pipe for conducting heated fluid from the furnace, of an adjustably mounted lever, a connection between the lever and the damper, a connection between the lever and the door, a thermostat attached to and adapted to be actuated by the heat of the contents of the pipe, and an adjustable lost motion connection between the thermostat and the said door and lever connection.

In testimony that I claim the foregoing as my own, I have hereto affixed my signature.

JOHN GOLDBERG.
